RALPH C. JAPPE, NOW BY JUDICIAL CHANGE OF NAME RALPH C. STEVENSON, OF BROOKLYN, NEW YORK, ASSIGNOR TO CONTINUOUS FORM PRINTING CO. INC., OF BROOKLYN, NEW YORK, A CORPORATION OF NEW YORK.

WEB FEEDING AND COLLECTING MECHANISM.

Application filed January 31, 1922. Serial No. 533,103.

To all whom it may concern:

Be it known that I, RALPH C. JAPPE (now by judicial change of name RALPH C. STEVENSON), a citizen of the United States, residing at the borough of Brooklyn, in the city of New York, county of Kings, and State of New York, have invented certain new and useful Improvements in Web Feeding and Collecting Mechanisms, of which the following is a specification, reference being had therein to the accompanying drawings, which form a part thereof.

My invention relates to a web feeding and collecting mechanism, and more particularly to a machine adapted to produce manifolding forms for use in billing and other machines, or for being filled in by hand.

Manifolding sheets or webs must be so made that the parts of the forms upon each sheet will be in reasonably accurate register with the corresponding parts of the forms on other sheets in each unit, so that all copies of a completely filled in form will be duplicates one of the other, and the printed or written matter inserted in one form will be properly located in the blanks provided therefor upon all other forms without being itself illegible and without obscuring a printed portion of any form.

The strips or webs which are fed and collected by means of a machine embodying my invention, are printed before delivery to the machine, the purpose of the machine being to feed a plurality of different printed strips or webs, each from its own roll, to superimpose the different strips or webs upon, and bring them into the desired registering relation to each other, and to advance the superimposed strips or webs simultaneously and to the same extent, so that irrespective of the length of a run of the machine, any slight error in some portion of the feeding mechanism will be compensated for by other portions of said feeding mechanism, or be corrected thereby in a manner to ensure substantially exact register of the printed forms upon the different superimposed sheets of each manifolding form.

The mechanisms of the machine of my invention are such that the different sheets of each manifolding form may be of the same, or different, colors or of the same,

or different, weights of paper, the function of the machine being the same irrespective of the weight or quality of the paper.

55

In connection with the mechanisms for collecting and advancing the web or strip of printed forms, I provide mechanisms which may be used to apply adhesive within, and adjacent, the edges of the various strips so that when the webs or strips have been once accurately positioned and advanced to the desired extent, their relation will be preserved. The manner of bonding the edges of the strip is such, however, as to admit of the ready separation of the sheets of each manifolding form after the blanks have been filled in, and thus permit the proper distribution of the various sheets of each form in conformity with the conditions required by the commercial system in connection with which the manifolding forms are to be used.

The construction of the machine is such that any desired number of sheets may be included in each manifolding form, it being possible by a mere readjustment of the gluing or pasting mechanisms, to adapt the machine for assembling a single or a plurality of sets of manifolding strips or webs, thus permitting an increased capacity of the machine when but few sheets are required in each manifolding form, by operating the machine at full capacity, but dividing this capacity so as to produce a plurality of sets of manifolding forms at the same time.

To secure the desired exact register of the printed matter upon superimposed sheets of each manifold form, I preferably provide mechanisms whereby with each cycle of the machine, a substantially uniform length of strip or web will be drawn from each supply roll, each strip or web having registering openings therethrough affording a gripping space adapted to be engaged by a feeding device for simultaneously imparting similar rectilineal movement to each of the strips or webs prior to the bonding of an edge or edges thereof when such bonding is done, thus compensating for any slight variation in the functioning of the mechanism for withdrawing the strips or webs from their several rolls, which last named mechanism will effectively

90

95

100

correct any error due to the functioning of the mechanism for drawing the strips or webs from the various supply rolls.

During the rectilineal movement above referred to, the several strips or webs are brought into parallel planes to facilitate the subsequent superimposing of the strips or webs one directly upon another, and in contact with each other, so as to permit all of them to be fed as a unit in the proper registered relation, by a delivery mechanism.

Before the several strips or webs are brought together, at said delivery mechanism, they are held apart so that adhesive may readily be applied at or near the edges, and between, adjacent strips or webs, the delivery mechanism, when adhesive is thus used, effecting a sealing of the strips or webs as an incident to the delivery thereof.

The arrangement of parts is such that at all times while the strips or webs are being fed with the printed forms thereon in registering position, they will be held sufficiently taut to prevent any such sagging as will permit any strip or web to sag to an extent to cause a loss of register of the forms on any of the strips or webs.

During the collecting of the various strips or webs, and the greater portion of the time while these webs or strips are being fed in unison, each strip or web will be in large measure separately controlled during the final stages of their process through the machine, all of the strips or webs will pass through presser rollers constituting the delivery mechanism which will act upon the pile as a unit.

The machine of my invention may be used to provide various groupings of original and duplicate sheets in manifolding forms, and to effect a different manner of sealing the edges thereof so as to produce various arrangements of these forms to conform to different commercial systems or the requirements of different forms of machines.

The invention consists primarily in a web feeding and collecting mechanism embodying therein supports for a plurality of rolls of printed strips or webs, means simultaneously drawing the strip or web from each of said rolls and superimposing said strips or webs one upon another with the printed matter upon each sheet in exact register with that upon the other sheets, and means arranged between said feeding means and the delivery point of the machine, whereby said strips or webs, with the printed matter thereon in register, are collectively fed in unison; and in such other novel features of construction and combination of parts as are hereinafter set forth and described, and more particularly pointed out in the claims hereto appended.

Referring to the drawings,

embodying one form of my invention, with portions thereof broken away;

Fig. 2 is a plan view thereof;

Fig. 3 is a more or less diagrammatic view illustrating the relation of the strips or webs during the feeding interval and the means for setting the machine for different widths of strips or webs;

Fig. 4 is a section on the line 4-4 of Fig. 2 upon an enlarged scale;

Fig. 5 is a section on the line 5-5 of Fig. 4;

Fig. 6 is an enlarged detail view of opposite ends of the feeding mechanism taken on the line 6-6 of Fig. 7;

Fig. 7 is a plan view broken away, of the mechanism shown in Fig. 6;

Fig. 8 is a perspective view of one end of the feed roller releasing mechanism;

Fig. 9 is a perspective view of the mechanism for imparting rectilineal feeding movement to the strips or webs;

Fig. 10 is a detail view in perspective of one of the gripper feed mechanisms;

Fig. 11 is a side view of one of the gripper feed mechanisms and one of the strip or web holding mechanisms associated therewith;

Fig. 12 is a perspective view of a product of the machine shown in Figs. 1 to 11; and

Figs. 13 to 21 illustrate different arrangements of manifolding forms which may be produced upon a machine of the type embodying my invention.

Like numerals refer to like parts throughout the several views.

In the embodiment of my invention shown in the drawings, the construction and arrangement of parts is such that the strips or webs to be fed and collected, superimposed one upon another, are fed through the machine with an intermittent movement, each feeding movement drawing a fixed, predetermined and uniform length of strip or web from each roll thereof in the ma-

chine, the length of each strip or web thus fed being determined by the mechanisms of the machine. Substantially accurate register of the printed matter upon the different strips or webs is secured by means of properly spaced openings in each strip or web, adapted to be engaged by some part of the feeding mechanism of the machine. It is apparent that, considering the invention in its broader aspects, a continuously operative feeding mechanism may be used instead of the intermittently operative feeding mechanism shown in the drawings, so long as the initial feeding movement for each strip or web is entirely independent of the mechanism operative upon the other strips or webs, and means are provided whereby

when a proper registering relation of the different strips or webs is once secured; the subsequent feeding of such strips or webs

115

120

125

130

may be controlled so as to ensure uniformity in the length of each strip or web advanced through the machine with each cycle thereof.

5 Referring particularly to the specific embodiment of the invention shown in the drawings, I provide at one end of the machine, bearings for a plurality of rolls of strip or web 30, 31, 32, 33, 34, 35, 36, 37, 38 10 and 39, each strip or web having printed thereon a repetition of appropriate or similar printed forms, a portion of each form being adapted to register with corresponding portions in different forms. Said strips 15 or webs are printed and collected in roll form prior to their delivery to the machine of my invention. The arrangement of the bearings for the various rolls 30 to 39 is immaterial, so long as it is such that the 20 strip or web from each roll may be brought to a single collecting point by means of which the various strips or webs may be superimposed one upon another.

Adjacent the various bearings for the 25 rolls of strip or web, I provide feed rollers adapted with each cycle of operation of the machine, to draw a fixed length of web or strip from each roll, the web or strip thus withdrawn being of substantially the length 30 of a printed form or forms upon the strips or webs, and the quantity so drawn from the several rolls being substantially uniform with each cycle of the machine.

As shown in the accompanying drawings, 35 the same feed rollers may be used to advance the strips or webs from a plurality of rolls, it being desirable, when a large number of strips or webs are to be simultaneously collected, that a plurality of similar 40 and simultaneously operative feed rollers be employed, each operative upon a plurality of strips or webs and each simultaneously operative to the same extent as the other. By thus dividing the total number of strips 45 or webs into a plurality of groups, the likelihood of error is minimized, although in the further handling of each strip or web, provision is made for correcting such error.

The error above referred to will arise 50 from the fact that when a plurality of strips or webs are passing between two rollers, the operative effect of the power roller will be such as to give a slightly greater feeding movement to the outer strips or webs, even 55 though the paper used be thin.

With a machine having high capacity, the accumulated error in time will be sufficient 60 to result in a relative position of the different strips or webs which will prevent correction of this error by other mechanisms in the machine. Hence the feed roller mechanism is so constructed and operated as to correct any error which develops during each cycle of the machine, thus permitting 65 the feeding mechanism to operate with sub-

stantial uniformity with relation to the feeding movement of the strips or webs thereto.

Referring more particularly to the mechanism shown in the drawings, I employ two 70 pairs of feed rollers 40—41, and 42—43, the detailed construction of the feed rollers 40 and 42 being identical, so that a description of but one of such mechanisms is essential. Each of these feed rollers consists of a metallic roller keyed to a shaft 44 which shaft carries the ratchet wheel 45 upon each end thereof. Idly mounted upon each end of the shaft 44 is a gear wheel 46 carrying one or more spring-pressed pawls 47 in operative relation to the ratchet wheel 45. Slidably mounted upon the frame of the machine is a carriage 48 carrying at opposite sides thereof racks 49 adapted to mesh with the gear wheels 46, the rack 49 being a 80 double rack so as to simultaneously and similarly actuate the wheels 46 through which the rolls 40 and 42 respectively are actuated.

The carriage 48 is mounted upon the main 90 frame of the machine by means of the bearing rollers 50 oppositely arranged in pairs so as to permit the free movement of said carriage. Any other desired means for supporting and guiding the carriage in its 95 movements may be employed if desired, the roller supports shown being a mere mechanical expedient which may be varied at will.

The carriage 48 is adapted to be reciprocated by means of the levers 51 upon opposite sides of the machine, which levers respectively are pivotally connected with said carriage and with compensating links 52, thus permitting reciprocatory movement to 100 be imparted to said carriage by means of crank wheels 53, the cranks of which are pivoted in slides 54 each mounted in an elongated slot 55 in each lever 51. The said crank wheels are actuated at the desired 110 R. P. M. through the gear train 56 deriving its power from the main power shaft 57 of the machine, which shaft carries an ordinary fly wheel 58.

By employing a crank wheel construction as described, the operative feeding effect of the carriage 48 will be such as to permit the starting of the feeding movement by the mechanisms mounted upon said carriage, at low speed, and an initial return movement 115 of the carriage at low speed, so as to minimize any tendency of the gripper mechanisms, to be hereinafter referred to, to tear or otherwise mutilate the strips or webs in a manner which would interfere with accuracy in the functioning of this mechanism.

Mounted upon, and movable with, the carriage 48 is a cross bar 59 having adjustably mounted thereon pendant brackets 60—61 130

each of which brackets carries a plurality of vertically alined grippers each consisting of a fixed tongue platen 62 slotted and having an upturned end as shown, which tongue is 5 adapted to be engaged by a spring gripper tongue 63 carried by, and formed integrally with, the platen 62 so that with movement in one direction, it will be adapted to operatively engage the paper strip or web to 10 be fed thereby, through the medium of a slot or depression in the strip or web, indicated at *a* in Figs. 9, 10, and 11, while during movement in the opposite direction, it will pass freely over the paper strip or web. 15 All of the gripper mechanisms are similarly constructed, their arrangement being such that the spring tongue 63 of each gripper mechanism will bear upon the platen 62 of the gripper immediately below same and 20 adjacent the slot formed therein.

By adjustably mounting the brackets 60 and 61 upon the cross bar 59, the machine may be adjusted so as to accommodate it to strips or webs of different widths, the set 25 screws 64 being employed to hold said brackets and the grippers carried thereby in any adjusted position.

The extent of projection of the tongue above the platen 62 beyond the plane of the 30 platen, is very slight being merely sufficient to ensure the desired engagement of the spring gripper member 63 therewith through the slot *a* in the paper, in a manner to ensure the desired feeding movement of 35 the strip or web, the amount of projection being insufficient to interfere with the idle movement of the grippers after they have completed one feeding movement and while 40 they are returning preparatory to a subsequent feeding movement.

Carried by the frame of the machine beyond the cross bar 59 and in the direction of the feeding movement of each strip or web, is a pair of feed rollers 65—66 between 45 which all of the strips or webs of paper, after they have been accurately registered and fed by the various grippers 62 and 63, pass while closely juxtaposed one upon another, the feeding movement of said rollers being substantially the same as that of the feed rollers 40—41 and 42—43.

One of said rollers as 66 is idly mounted and spring-pressed toward the roller 65, said last named roller being intermittently 55 rotated by means of a ratchet wheel 67 carried by the shaft to which said roller 65 is keyed, and a gear wheel 68 idly mounted upon said shaft and carrying one or more spring-pressed pawls 69 adapted to co-operate with said ratchet wheel, this actuating mechanism being duplicated upon opposite sides of the machine.

The gear wheels 68 are actuated by means 60 of the racks 70 carried upon opposite sides 65 of the carriage 48, which racks correspond,

as to the timing of the actuation of the roller 65, with the functioning of the racks 49 with relation to the rollers 40 and 42, differing therefrom merely in that the latter racks are double, as shown more particularly in Fig. 70 6, while the racks 70 are but single racks, since but one pair of feed rollers is actuated thereby.

It will be observed from the foregoing 75 that while in drawing the strips or webs from the several rolls thereof, a plurality of such strips or webs will pass while in contact between feeding rollers, that each strip will thereafter receive rectilineal feeding movement by means of a mechanism individually 80 operative thereon, and that while being fed rectilineally and in parallel planes, each strip or web will be so positioned as to bring the printed matter thereon in exact register with the printed matter upon the other strips 85 or webs, and that after the various strips or webs have thus been individually fed and brought into registering relation, they are again brought together so that upon the subsequent feeding movement of the carriage, 90 said webs or strips are again brought into close juxtaposition and all of the assembled strips simultaneously fed prior to their delivery from the machine.

To prevent a possible return movement of 95 the various strips or webs being assembled and fed, as a result of a return movement of the platens 62 and the grippers 63, I provide holding grippers between the bar 59 and the feed rollers 65 and 66, which grippers are so formed and set that they permit the strips to be drawn freely therethrough by said rollers 65 and 66, but prevent movement of said strips or webs in the reverse 100 direction under the control of the grippers 63.

This holding gripper mechanism consists of brackets 71—72 adjustably mounted upon a cross bar 73 carried by the frame of the machine, said brackets 71 and 72 carrying a plurality of platens 74 and grippers 110 75 constructed and set similarly to the platens 62 and grippers 63. There is a difference in the functioning, however, of the platens 74 and grippers 75 and the platens 62 and the grippers 63, in that while the latter co-operate with openings *a* formed in the strips or webs for a purpose which will 115 more fully appear hereinafter, the former are adapted to operatively engage any portion of each strip or web, since when said strips or webs have been advanced to the full extent under the control of the carriage 48 and the grippers carried thereby, the proper registration has already been effected, thus relieving the platens 74 and the 120 grippers 75 of any registering function, their function being merely to hold the sheet against a return movement with a possible 125 resulting loss of register.

By employing rectilineally movable grip-

pers, or a feeding means which will advance the strips or webs in parallel relation one to the other, and by providing a gripper mechanism co-operating with fixed points of each strip or web, I am enabled to ensure absolute uniformity in the operative effect of the feeding movement. The passage of a plurality of such strips or webs between a pair of feeding rollers is apt to introduce a small degree of error in the quantity of some of the sheets fed, which error, however, will not seriously interfere with a proper registration of the forms upon the different strips or webs, provided it is not permitted to accumulate during a long run of the machine.

When employing a reciprocatory carriage with gripper mechanisms as described, the use of feeding rollers such as 40—41 and 42—43 is desirable, since it relieves the paper from substantially all pulling stresses by the feeding grippers, since these rollers will create slack in the strips or webs, or advance them toward the said grippers during their feeding movement as said grippers advance in their feeding movement.

I have found it desirable, however, to so construct said feed rollers that with each cycle of the machine, the co-operating feed rollers 40—41 and 42—43 will be disengaged one from the other so as to relieve the sheets between same from pressure and thus permit the paper through the stretch inherent thereto to impart a sufficient return movement to any slack in the strip or web adjacent said rollers, or formed as a result of the grippers 62 and 63 advancing toward said feed rollers, and thus prevent the accumulation of an excess of paper between said feed rollers and the grippers moving with said carriage.

It will be readily understood that this method of correcting error is practicable merely because the feed rollers are separated with each cycle of operation of the machine, and that the error when it exists is so small that even though it be not corrected for a full cycle, this error, which may be termed a single error, would not affect registration. The excess speed of some of the sheets is so slight that the spring of the paper itself will be sufficient to correct same when the pressure thereon from the feeding rollers is once relieved.

To secure a proper timing in the release of the pressure upon the strips or webs from the rollers 40—41 and 42—43, I mount the rollers 41 and 43 in journal housings 76 and 77 respectively, slidably mounted in ways in the frame of the machine, said journal housings being respectively acted upon by a spring 78 having a normal tendency to thrust the rollers 41 and 43 into engaging relation with the strips or webs passed about the rollers 40 and 42. Acting upon each of

the housings 76 and 77 is a cam shaft 79—80 idly mounted upon opposite ends of each of which is a spring-pressed latch member 81 or 82, each of said latch members carrying a contact roller 83 as shown more particularly in Fig. 8, adapted to operatively engage a projection upon said cam shaft and rotate same so as to move the journal housings 76 and 77 against the tension of their springs 78, and thus separate the feed rollers of each pair. The latch members 81 and 82 project toward each other and into the path of an actuating bar 84, carried by the racks 49 respectively, this bar being of a length to engage and hold said latch members in a position to maintain the rollers 41 and 43 out of the operative relation to the strips or webs passed about the rollers 40 and 42 during substantially the entire return movement of the carriage 48 during which, said feed rollers 40 and 42 are inoperative to impart feeding movement to the strip or web. Toward the end of this return movement, said bar will pass beyond the members 82 and 83 so as to permit the return of the rollers 41 and 43 into engaging relation with the strips or webs prior to the initial direct feeding movement of the carriage 48.

Upon opposite sides of the main frame of the machine, I provide pasting mechanisms by means of which a small quantity of adhesive may be applied adjacent opposite edges of the strips as they are fed through the machine, so that as all of the strips or webs are brought together in contact they will be permanently secured together in a manner which will ensure permanency in their registering relation while permitting a separation of the sheets constituting each manifolding form after the blanks have been filled in and after the continuous strips of such forms have been separated into individual forms, whether this is done before the blanks have been filled in or after they have been so filled in. Paste or glue is applied to the several strips or webs while they are moving in parallel planes, and spaced apart, and before the various strips or webs converge and pass between the delivery rollers 65 and 66, so that these rollers will develop that pressure necessary to not only secure the desired delivery movement of the collected strips or webs, but will apply that pressure necessary to properly seal the pasted edges of adjoining strips or webs.

In the embodiment of my invention shown in the drawings, the specific pasting mechanism is shown as being composed of paste reservoirs upon opposite sides of the main frame of the machine mounted upon guide rods, said reservoirs being shown at 85 and 86 and the guide rods at 87 and 88.

The paste reservoirs are each supported by a suitable frame having rotatably mount-

ed therein a disk 89, the lower edge of which is adapted to pass through the liquid paste or glue in the reservoir, and to transfer a portion of the paste accumulated thereon to 5 a sequence of horizontally rotatable paste wheels 90, each of which has a reduced edge adapted to enter between the strips or webs being fed.

The disks 89 are adapted to be rotated 10 from the main shaft of the machine by the belt and pulley mechanism 91, the belt of said mechanism being crossed so as to cause a movement of the wheels 90 coincident with the movement of the strips or webs 15 with which they engage.

Preferably paste reservoirs are adjustable laterally of the machine upon the rods 87 and 88 by means of the right and left handed lead screw 92 with the four-fold 20 object of regulating the quantity and location of the adhesive applied to the strips or webs, permitting readjustment of the machine for securing various groupings of the strips or webs to produce different mani- 25 folding forms while running a machine to capacity, adapting the pasting mechanism to strips or webs of different widths, or permitting either or both said pasting mechanisms to be made entirely inoperative if 30 it be desired to not paste the edges of the strips or webs.

Preferably the wheels 90 will be positioned closely adjacent the holding gripper 75 and between same and the delivery pressure rollers 65 and 66 so that the convergence of the strips from adjacent said grippers toward said rollers will ensure the desired engagement of these strips or webs with said wheels.

40 Preferably I provide adjacent the paper feed rollers 40-41 and 42-43 spaced guides indicated at 93 in Fig. 3 of the drawings, although I do not consider such at all essential, since the construction of the 45 platen and gripper mechanisms 62 and 63 will effectively separate the strips if there is any tendency of their adhering one to the other as a result of the pressure of the feed rollers thereon.

50 While in the drawings I have shown the assembled strip of manifolding forms as being collected in a fan-fold form, I have not shown the mechanism for giving them this form, since the form in which the strips 55 are delivered is immaterial to my present invention, and any desired mechanism for this purpose may be used.

The operation of the herein described mechanism is substantially as follows:—

60 Preparatory to delivering the rolls 30 to 39, inclusive, to the herein described machine, the desired forms are printed upon each of said rolls, the slots or depressions α being formed in each paper strip or web as 65 it is printed, so that these depressions or

slots will all occupy the same position with relation to the printed matter on the form and will be spaced longitudinally of the strip or web equal distances coinciding with the quantity of feeding movement which 70 each strip or web must receive while in the feeding and collecting mechanism, to ensure substantially accurate registering of the forms upon different strips or webs. When it is desired to collect and feed the 75 various strips or webs, the spindle carrying same is mounted upon the bearings therefor in the machine, which bearings, in the form of the invention shown, consist of studs having collars thereon adapted to permit accuracy in the lateral adjustment of the various rolls of strip or web. The collars may be so adjusted that the rolls will be subjected to continuing friction so as to always place the strip or web being drawn 80 therefrom under sufficient tension to ensure the strip or web being fed perfectly smooth from each roll and always maintain the strip or web withdrawn therefrom fairly 85 taut.

90 After the rolls have been mounted in the machine, the end of each strip or web is passed about one or the other of the feeding rollers 40-42, through the guides 93 when such are used, and between a gripper tongue 95 63 of the movable gripper mechanism and the platen 62 of the next gripper immediately below same. The free end of each strip or web is then passed between the platen and gripper mechanisms 74 and 75 and the delivery 100 presser rollers 65 and 66. In threading each strip or web through the machine, the slots α upon each strip should be brought into a position where they will approximately be 105 in engaging relation to the gripper tongues 63, it being assumed that the machine when threading the strips or webs therethrough will have the parts so positioned as to engage the feed rollers 40-41 and 42-43.

110 When the strips or webs have been properly threaded through the machine, power may be applied thereto and thereafter the machine will function automatically to advance each strip or web to the same extent as every other strip or web, excepting as to 115 such slight deviation as may be necessary to correct error in some of the mechanisms of the machine in order that the forms upon the various strips may be brought into substantially accurate registering relation. In the continued functioning of the machine, however, the ultimate feeding movement of the various strips or webs with each cycle of the machine, will be the same as to each strip or 120 web.

125 Assuming that the various strips or webs have been properly threaded through the machine and that the carriage 48 is in the extreme position to the left (Fig. 1), the rotation of the crank disk 53 will, through the 130

block 54 and the lever 51, impart movement to the carriage to the right until the parts have assumed the position shown in full lines Fig. 1. During this movement, the 5 racks 49 will turn the gear wheels 46, causing the rollers 40—41 and 42—43 to draw a length of strip or web between said rollers from the rolls 30 to 39 respectively, (according to the grouping of the strips or webs in 10 relation to said feeding rollers) a distance approximating that required for the feeding movement of the gripper mechanism movable with said carriage. This movement of the carriage 48 will engage the various 15 gripper tongues 63 each with a strip or web through the medium of the slots *a* therein, and thus take up slack as it is formed, resulting from the feeding movement of said feed rollers.

20 By the slot and tongue construction of the platen 62, any possibility of the gripper tongue 63 riding upon the paper without imparting movement thereto, is avoided, although the construction is such that no feeding movement will be imparted to any strip or web until said tongue 63 has engaged its co-operating platen 62 through the slot *a* in the paper, or if a depression is relied on, by the forcing of the depression into the slit 30 in the platen 62 adjacent the tongue of said platen.

The spacing of the various gripper tongues 63 will separate the various strips or webs being fed, and maintain them in a 35 substantially parallel arrangement, or upon substantially parallel planes.

As the various strips or webs are advanced by the gripper tongues 63 and their co-operating platens 62, the movement of the 40 carriage 48 will, through the racks 70, actuate the delivery rollers 65 and 66 so that these rollers will take up slack as it is created by the movement of said carriage and said gripper tongues, thus drawing that portion 45 of the strips or webs beyond said gripper tongues through the holding grippers 74 and 75 while still keeping the various strips or webs sufficiently taut.

As the various strips or webs pass the 50 paste wheels 90 entering between parallel strips or webs, the rotary movement of said wheels will apply a thin film of paste or other adhesive to one or both of the adjacent surfaces of said strips, the strips after passing said paste wheels converging toward each other until they are brought and 55 pressed into contact by the rollers 65 and 66 which will effect the final collection of the various strips or webs and firmly cement 60 them together.

During the initial feeding movement of the carriage 48, the crank pin upon the disk 53 will be moving from a horizontal center, thus imparting a slow initial movement with 65 gradually increasing speed, to the carriage,

and toward the end of the feeding movement when the crank pin is passing toward the opposite horizontal center, there will be a gradual slowing down of the movement. By mounting the actuating racks 49 and 70 upon 70 said carriage, however, the feed and the delivery rollers will have a peripheral speed determined by the lineal speed of said carriage, thus avoiding any material looseness 75 in the strips or webs during the feeding thereof.

After the crank wheel 53 has made one complete revolution, a return reciprocatory movement will be imparted thereby to the carriage 48, with the same varying 80 speed conditions as are above referred to. During this return movement, the delivery rollers 65 and 66 will be idle by reason of the pawl and ratchet mechanism connecting the gears 68 with the roller 65 and the feed rollers will remain idle by reason of the pawl and ratchet mechanism connecting the gears 46 with the rollers 40 and 42 respectively. Hence the feed rollers and the delivery rollers will be inoperative during 85 the return movement of said carriage 90 and will be operative only during the feeding movement thereof.

As the carriage moves to the left (Fig. 95 11), the gripper tongues 63 being of spring metal, will yield sufficiently to permit them and the platens 62 to slide freely over the strip or web engaged thereby, and will at the same time have a smoothing or straightening action adjacent the edges of said strip or web so as to cause accuracy in the measured feeding movement of said grippers. As the platen and gripper mechanisms 62 and 63 thus move contra to their feeding 100 movement and away from the holding grippers 74 and 75, these grippers will engage and restrain any return movement of each strip or web. During the initial return movement of the carriage 48, the bar 84 thereon will engage the latch members 81 and 82 and oscillate them in a manner to rock the cam shafts 81 through the medium of the impact member 84, thus forcing the journal housings 76 and 77 away from the feed rollers 40 and 42 to an extent to relieve pressure upon the strips or webs between each pair of feed rollers, and permit the elasticity inherent to said strips to impart a slight return movement thereto 105 in the event that any slack is present between said feed rollers and the travelling gripper mechanism. If fairly heavy paper be used, the thrust upon the paper by the platen and gripper mechanisms 62 and 63 110 will also have a tendency to force the paper back between the feed rollers.

As the carriage 48 approaches the limit of its movement toward the feed rollers, the bar 84 will pass from its engagement 115 with the latch members 81 and 82, per-

mitting said latch members to return to their normal position, so that the springs 78 may force the journal housings 76 and 77 to their former position and the rollers 5 41 and 48 in engaging relation to the strips or webs between same and the rollers 40 and 42, thus positioning said feed rollers so that they will be operative upon the reversal of movement of the carriage. By 10 applying similar actuating mechanisms to the various parts upon opposite sides of the machine, I avoid possible skewing of the strips or webs.

It will be observed that while the strips 15 or webs are being fed under the control of the grippers 62-63, they will be having rectilineal movement in parallel planes, and that the vertical alinement of the various gripper tongues 63 will bring and maintain 20 the various strips or webs into exactly the same position with relation to each other so as to bring the printed forms upon the various strips into register.

By imparting a reciprocatory movement 25 to the carriage 48 slightly in excess of the required feeding movement of the strips or webs, there will be slight lost motion between the gripper tongues 63 and their platens 62 and the strip before said tongues 30 enter the slots *a*, this lost motion being preferably provided so that in the event of a slight staggered relation of said slots in different sheets, some of the gripper mechanisms 62 or 63 may operatively engage and impart feeding movement to 35 some strips or webs, before other gripper mechanisms have reached the operative relation to other strips or webs as defined by the location of the slots *a* therein.

40 The machine shown in the accompanying drawings is designed to superimpose ten strips or webs one upon the other, it being apparent, however, that any lesser number of strips or webs may be collected and fed 45 by the machine, irrespective of its maximum capacity of ten. It is also apparent that by increasing the number of gripper mechanisms and paste wheels, which will involve a mere duplication of parts, the number 50 of strips or webs thus collected and fed may be increased.

Since each strip or web after it leaves the feed rollers is individually controlled by a platen and gripper mechanism, it is apparent 55 that if desired ten different weights and colors of paper may be collected in a manifolding form, or any desired variation in the weight or coloring of the different sheets of a form may be secured.

60 Under some conditions it may be desired to merely collect and feed printed sheets with the matter thereon in register, without pasting the sheets together. Under such conditions the pasting wheels 90 may 65 be made inoperative with relation to the

strips or webs, or be entirely removed from the machine so as to avoid any paste about said edges. If it be desired to paste only one edge of the full ten sheets, one pasting mechanism may be made entirely inoperative, thus applying paste to only one edge of said strips or webs. By readjusting the machine by removing different paste wheels 70 90, and using spacers to position these wheels in any desired relation, the edges 75 of some of said strips or webs may be pasted on one side of the machine while the other strips or webs may be pasted on the other side of the machine. This condition exists when manifolding forms require less than the maximum number of strips or webs which may be handled by the machine. By thus adjusting the pasting mechanism, any desired grouping of the strips or webs in the completely collected and registered manifolding forms 80 85 may be secured, so that subsequently the different groupings may be separated and thus permit the machine to be used upon different jobs at the same time. 90

In Figs. 13 to 21 different products of the machine are illustrated.

In Fig. 13 the superimposed registered strips or webs are not pasted at all. In Fig. 14 they are pasted only on one edge. In Fig. 15 a number of strips are pasted on alternately opposite edges. In Fig. 16 some of the strips or webs are offset laterally with relation to others and the projecting edges of adjacent strips pasted. In Fig. 17 one 100 edge of alternate pairs of strips is pasted. In Fig. 18 alternate strips or webs on each side are pasted, the rolls of same being laterally offset so as to secure the result desired. In Fig. 19 both edges of all strips or webs 105 are pasted. In Fig. 20 a product is shown in which narrow strips are alternated with wide strips, and adjacent edges on both sides pasted so as to provide a form which may be unfolded. In Fig. 21 the construction is similar to that shown in Fig. 19, excepting that the strips are separated along their longitudinal center so that two sets of 110 dissimilar forms of narrow width may be produced. 115

Whatever the form of the product, all strips which enter into a single manifolding form, whether the blanks in each form are two or more, will be in exact register with each other, the pasting of the edges and the manner of doing same having absolutely nothing to do with the feeding and registering of the strips or webs, but being solely to maintain them in their registered relation.

It is not my intention to limit the invention to the precise details of construction shown in the accompanying drawings, it being apparent that such may be varied without departing from the spirit and scope 120 125 of the invention. 130

Having described the invention, what I claim as new and desire to have protected by Letters Patent, is:—

1. A web feeding and collecting mechanism embodying therein supports for a plurality of rolls of printed strips or webs, means simultaneously drawing the strip or web from each of said rolls and superimposing said strips or webs one upon another, 5 means imparting relative movement to said sheets, whereby they will be positioned with the printed matter upon each sheet in exact register with that upon the other sheets, and means arranged between said feeding means 10 and the delivery point of the machine, whereby said strips or webs, with the printed matter thereon in register, are collectively fed in unison.
2. A web feeding and collecting mechanism embodying therein supports for a plurality of rolls of printed strips or webs, means simultaneously drawing the strip or web from each of said rolls and superimposing said strips or webs one upon another, 15 means imparting relative movement to said sheets, whereby they will be positioned with the printed matter upon each sheet in exact register with that upon the other sheets, means arranged between said feeding means 20 and the delivery point of the machine, whereby said strips or webs, with the printed matter thereon in register, are collectively fed in unison, and means adapted to apply adhesive adjacent an edge of said 25 strips or webs respectively.
3. A web feeding and collecting mechanism embodying therein supports for a plurality of rolls of printed strips or webs, a plurality of feeding mechanisms operative 30 upon said strips or webs respectively and adapted to impart rectilineal movement thereto in parallel planes, said feeding mechanism including therein means whereby said strips or webs will be simultaneously withdrawn 35 from said rolls and so positioned with relation to each other as to be brought in position with the printed matter upon each sheet in accurate register with that upon the other sheets, and means arranged 40 between said feeding mechanisms and the delivery point of the machine, whereby said strips or webs, with the printed matter thereon in register, are brought together and collectively fed in unison.
4. A web feeding and collecting mechanism embodying therein supports for a plurality of rolls of printed strips or webs, a plurality of feeding mechanisms operative 45 upon said strips or webs respectively and adapted to impart rectilineal movement thereto in parallel planes, whereby said strips or webs will be simultaneously withdrawn 50 from said rolls and brought in position with the printed matter upon each sheet in accurate register with that upon the other 55 sheets, means adapted to apply adhesive adjacent to an edge of said strips or webs respectively while they are being fed in parallel planes, and means arranged between said feeding mechanisms and the delivery point 60 of the machine, whereby said strips or webs, with the printed matter thereon in register, are brought together and collectively fed in unison.
5. A web feeding and collecting mechanism embodying therein supports for a plurality of rolls of printed strips or webs, means simultaneously drawing the strip or web from each of said rolls and superimposing said strips or webs one upon another, 65 means including therein a projecting member adapted to engage successive accurately spaced openings or depressions in each strip or web, whereby the operative engagement of said means and the strip or web is determined by the strip or web and the printed matter on each strip or web is brought into accurate register with that upon the other sheets, and means arranged 70 between said feeding means and the delivery point of the machine, whereby said strips or webs, with the printed matter thereon in register, are collectively fed in unison.
6. A web feeding and collecting mechanism embodying therein supports for a plurality of rolls of printed strips or webs, a pair of feed rollers adapted to simultaneously draw a plurality of said strips or webs from the rolls thereof, a plurality of grippers each adapted to engage a strip or web, means whereby said grippers are reciprocated, operative connections between said last named means and said feed rollers, whereby said rollers will be actuated while said grippers are moving away from said 80 rollers and will be inoperative while said grippers are moving towards said rollers, means arranged between said grippers and the delivery point of the machine, whereby said strips or webs, with the printed matter 85 thereon in register, are brought together and collectively fed in unison, and actuating means for said last named means whereby it will be operative when said grippers are operative to feed the strips or webs, and will be inoperative when said grippers 90 are inoperative.
7. A web feeding and collecting mechanism embodying therein supports for a plurality of rolls of printed strips or webs, a pair of feed rollers adapted to simultaneously draw a plurality of said strips or webs from the rolls thereof, a plurality of grippers each adapted to engage a strip or web, means whereby said grippers are reciprocated, operative connections between said last named means and said feed rollers, whereby said rollers will be actuated while said grippers are moving away from said 95 rollers and will be inoperative while said 100 grippers are moving towards said rollers, means arranged between said grippers and the delivery point of the machine, whereby said strips or webs, with the printed matter 105 thereon in register, are brought together and collectively fed in unison, and actuating means for said last named means whereby it will be operative when said grippers are operative to feed the strips or webs, and will be inoperative when said grippers 110 are inoperative.
8. A web feeding and collecting mechanism embodying therein supports for a plurality of rolls of printed strips or webs, a pair of feed rollers adapted to simultaneously draw a plurality of said strips or webs from the rolls thereof, a plurality of grippers each adapted to engage a strip or web, means whereby said grippers are reciprocated, operative connections between said last named means and said feed rollers, whereby said rollers will be actuated while said grippers are moving away from said 115 rollers and will be inoperative while said grippers are moving towards said rollers, means arranged between said grippers and the delivery point of the machine, whereby said strips or webs, with the printed matter 120 thereon in register, are brought together and collectively fed in unison, and actuating means for said last named means whereby it will be operative when said grippers are operative to feed the strips or webs, and will be inoperative when said grippers 125 are inoperative.
9. A web feeding and collecting mechanism embodying therein supports for a plurality of rolls of printed strips or webs, a pair of feed rollers adapted to simultaneously draw a plurality of said strips or webs from the rolls thereof, a plurality of grippers each adapted to engage a strip or web, means whereby said grippers are reciprocated, operative connections between said last named means and said feed rollers, whereby said rollers will be actuated while said grippers are moving away from said 130 rollers and will be inoperative while said grippers are moving towards said rollers, means arranged between said grippers and the delivery point of the machine, whereby said strips or webs, with the printed matter thereon in register, are brought together and collectively fed in unison.

- grippers are moving towards said rollers, means arranged between said grippers and the delivery point of the machine, whereby said strips or webs, with the printed matter thereon in register, are brought together and collectively fed in unison, fixed holding grippers between said first named grippers and said last named means, and actuating means for said last named means whereby it will be operative when said grippers are operative to feed the strips or webs, and will be inoperative when said grippers are inoperative.

8. A web feeding and collecting mechanism embodying therein supports for a plurality of rolls of printed strips or webs, a pair of feed rollers adapted to simultaneously draw a plurality of said strips or webs from the rolls thereof, a plurality of grippers each adapted to engage a strip or web, means whereby said grippers are reciprocated, operative connections between said last named means and said feed rollers, whereby said rollers will be actuated while said grippers are moving away from said rollers and will be inoperative while said grippers are moving toward said rollers, means whereby said feed rollers are separated while they are inoperative, means arranged between said grippers and the delivery point of the machine, whereby said strips or webs, with the printed matter thereon in register, are brought together and collectively fed in unison, and actuating means for said last named means whereby it will be operative when said grippers are operative to feed the strips or webs, and will be inoperative when said grippers are inoperative.

9. A web feeding and collecting mechanism embodying therein supports for a plurality of rolls of printed strips or webs, a pair of feed rollers adapted to simultaneously draw a plurality of said strips or webs from the rolls thereof, a plurality of grippers each adapted to engage a strip or web, means whereby said grippers are reciprocated, operative connections between said last named means and said feed rollers, whereby said rollers will be actuated while said grippers are moving away from said rollers and will be inoperative while said grippers are moving toward said rollers, means whereby said feed rollers are separated while they are inoperative, means arranged between said grippers and the delivery point of the machine, whereby said strips or webs, with the printed matter thereon in register, are brought together and collectively fed in unison, fixed holding grippers between said first named grippers and said last named means, and actuating means for said last named means whereby it will be operative when said grippers are operative to feed the strips or webs,

10. web feeding and collecting mechanism embodying therein supports for a plurality of rolls of printed strips or webs, a pair of feed rollers adapted to simultaneously draw a plurality of said strips or webs from the rolls thereof, gears idly mounted adjacent one of said rollers, pawl and ratchet wheel connections between said gears respectively and said rollers, a reciprocatory frame, racks thereon co-operating with said gears, said pawl and ratchet wheel connections being so set that with the movement of said frame toward said rollers, no power will be transmitted from said wheels to said rollers, and with the movement of said frame away from said rollers, said rollers will be actuated, a plurality of grippers carried by said frame, each of said grippers being adapted to engage a strip or web, means arranged between said grippers and the delivery point of the machine, whereby said strips or webs, with the printed matter thereon in register, are brought together and collectively fed in unison, said means having no movement with said frame, and actuating means for said last named means whereby it will be operative when said rollers are operative, and will be inoperative when said feed rollers are inoperative.

11. A web feeding and collecting mechanism embodying therein supports for a plurality of rolls of printed strips or webs, a pair of feed rollers adapted to simultaneously draw a plurality of said strips or webs from the rolls thereof, gears idly mounted adjacent one of said rollers, pawl and ratchet wheel connections between said gears respectively and said roller, a reciprocatory frame, racks thereon co-operating with said gears, said pawl and ratchet wheel connections being so set that with the movement of said frame toward said rollers, no power will be transmitted from said wheels to said rollers, and with the movement of said frame away from said rollers, said rollers will be actuated, a plurality of grippers carried by said frame, each of said grippers being adapted to engage a strip or web, means arranged between said grippers and the delivery point of the machine, whereby said strips or webs, with the printed matter thereon in register, are brought together and collectively fed in unison, said means having no movement with said frame, fixed holding grippers between said first named grippers and said last named means, and actuating means for said last named means whereby it will be operative when said rollers are operative, and will be inoperative when said feed rollers are inoperative.

12. A web feeding and collecting mech-

- anism embodying therein supports for a plurality of rolls of printed strips or webs, a pair of feed rollers adapted to simultaneously draw a plurality of said strips or webs from the rolls thereof, a plurality of grippers each adapted to engage a strip or web, each of said grippers comprising a platen having a slit therein, and a resilient tongue, said grippers being arranged one above another with said tongues in vertical alinement, whereby the tongue of one gripper will co-operate with the platen of the gripper immediately below, means whereby said grippers are reciprocated, operative connections between said last named means and said feed rollers, whereby said rollers will be actuated while said grippers are moving away from said rollers and will be inoperative while said grippers are moving towards said rollers, means arranged between said grippers and the delivery point of the machine, whereby said strips or webs, with the printed matter thereon in register, are brought together and collectively fed in unison, and actuating means for said last named means whereby it will be operative when said grippers are operative to feed the strips or webs, and will be inoperative when said grippers are inoperative.
13. A web feeding and collecting mechanism embodying therein supports for a plurality of rolls of printed strips or webs, a pair of feed rollers adapted to simultaneously draw a plurality of said strips or webs from the rolls thereof, a plurality of grippers each adapted to engage a strip or web, each of said grippers comprising a platen having a slit therein, and a resilient tongue, said grippers being arranged one above another with said tongues in vertical alinement, whereby the tongue of one gripper will co-operate with the platen of the gripper immediately below, means whereby said grippers are reciprocated, operative connections between said last named means and said feed rollers, whereby said rollers will be actuated while said grippers are moving away from said rollers and will be inoperative while said grippers are moving towards said rollers, means arranged between said grippers and the delivery point of the machine, whereby said strips or webs, with the printed matter thereon in register, are brought together and collectively fed in unison, fixed holding grippers between said first named grippers and said last named means, each of said grippers consisting of a platen member having a slit therein, and a resilient tongue, said grippers being arranged one above another with said tongues in vertical alinement, whereby the tongue of one gripper will co-operate with the platen of the gripper immediately below, and actuating means for said last named
- means whereby it will be operative when said grippers are operative to feed the strips or webs, and will be inoperative when said grippers are inoperative.
14. A web feeding and collecting mechanism embodying therein supports for a plurality of rolls of printed strips or webs, a pair of feed rollers adapted to simultaneously draw a plurality of said strips or webs from the rolls thereof, gears idly mounted adjacent one of said rollers, pawl and ratchet wheel connections between said gears respectively and said roller, a reciprocatory frame, racks thereon co-operating with said gears, said pawl and ratchet wheel connections being so set that with the movement of said frame toward said rollers, no power will be transmitted from said wheels to said rollers, and with the movement of said frame away from said rollers, said rollers will be actuated, a plurality of grippers carried by said frame, each of said grippers being adapted to engage a strip or web, a pair of feed rollers between said grippers and the delivery point of the machine, whereby said strips or webs, with the printed matter thereon in register are brought together and collectively fed in unison, gear wheels idly mounted adjacent one of said feed rollers, pawl and ratchet wheel connections between said gears respectively and said rollers, and racks on said frame co-operating with said last named gears, said last named pawl and ratchet wheel connections being so set that with the movement of said frame toward said feed rollers, no power will be transmitted from said wheels to said delivery rollers, and with the movement of said frame away from said rollers, said delivery rollers will be actuated.
15. A web feeding and collecting mechanism embodying therein supports for a plurality of rolls of printed strips or webs, a pair of feed rollers adapted to simultaneously draw a plurality of said strips or webs from the rolls thereof, slideable bearings for one of said rollers, cam shafts operative upon said bearings respectively, a spring-pressed latch member adjacent said shaft, a contact carried by said latch member and adapted to operate said cam shaft, gears idly mounted adjacent the other of said feed rollers, pawl and ratchet wheel connections between said gears respectively and said roller, a reciprocatory frame, racks thereon co-operating with said gears respectively, said pawl and ratchet wheel connections being so set that with the movement of said frame toward said rollers, no power will be transmitted from said wheels to said rollers, and with the movement of said frame away from said rollers, said rollers will be actuated, a bar carried by said frame in operative relation to said latch member, a plurality of grippers carried by said

frame, each of said grippers being adapted to engage a strip or web, means arranged between said grippers and the delivery point of the machine, whereby 5 said strips or webs, with the printed matter thereon in register, are brought together and collectively fed in unison, said means having no movement with said frame, and actuating means for said last named means whereby 10 it will be operative when said rollers are operative, and will be inoperative when said feed rollers are inoperative.

16. A web feeding and collecting mechanism embodying therein supports for a plurality of rolls of printed strips or webs, a plurality of pairs of feed rollers each adapted to simultaneously draw a plurality of said strips or webs from the rolls thereof, gears idly mounted adjacent one of the rollers of each pair, a pawl and ratchet wheel connection between each of said gears respectively and the roller with which it is associated, a reciprocatory frame, double racks on said frame passing between the gears of each pair of feed rollers and cooperating with said gears, said pawl and ratchet wheel connections being so set that with the movement of said frame toward said rollers, no power will be transmitted 20 from said wheels to said rollers, and with the movement of said frame away from said rollers, said rollers will be actuated, a plurality of grippers carried by said frame, each of said grippers being adapted to engage a strip or web, means arranged between said grippers and the delivery point of the machine, whereby said strips or webs, with the printed matter thereon in register, are brought together and collectively fed 30 in unison, said means having no movement with said frame, and actuating means for said last named means whereby it will be operative when said rollers are operative, and will be inoperative when said feed rollers are inoperative.

17. A web feeding and collecting mechanism embodying therein supports for a plurality of rolls of printed strips or webs, a plurality of pairs of feed rollers each adapted to simultaneously draw a plurality of said strips or webs from the rolls thereof, gears idly mounted adjacent one of the rollers of each pair, a pawl and ratchet wheel connection between each of said gears respectively and the roller with which it is associated, a reciprocatory frame, double racks on said frame passing between the gears of each pair of feed rollers and cooperating with said gears, said pawl and ratchet wheel connections being so set that with the movement of said frame toward said rollers, no power will be transmitted 40 from said wheels to said rollers, and with the movement of said frame away from said rollers, said rollers will be actuated, a plurality of grippers carried by said frame, each of said grippers being adapted to engage a strip or web, means arranged between said grippers and the delivery point of the machine, whereby said strips or webs, with the printed matter 50 thereon in register, are brought together and collectively fed in unison, fixed holding grippers between said first named grippers and said last named means, and actuating means for said last named means whereby it will be operative when said grippers are operative to feed the strips or webs, and will be inoperative when said grippers are inoperative.

18. A web feeding and collecting mechanism embodying therein supports for a plurality of rolls of printed strips or webs, a pair of feed rollers adapted to simultaneously draw a plurality of said strips or webs from the rolls thereof, a plurality of grippers each adapted to engage a strip or web, means whereby said grippers are reciprocated, operative connections between said last named means and said feed rollers, whereby said rollers will be actuated while 60 said grippers are moving away from said rollers and will be inoperative while said grippers are moving towards said rollers, means arranged between said grippers and the delivery point of the machine, whereby 70 it will be operative when said grippers are operative to feed the strips or webs, and will be inoperative when said grippers are inoperative.

19. A web feeding and collecting mechanism embodying therein supports for a plurality of rolls of printed strips or webs, a pair of feed rollers adapted to simultaneously draw a plurality of said strips or webs, with the printed matter thereon in register, are brought together and collectively fed in unison, gear wheels idly mounted adjacent one of said feed rollers, pawl and ratchet wheel connections between said gears respectively and said rollers, and racks on said frame co-operating with said last named gears, said last named pawl and ratchet wheel connections being so set that with the movement of said frame toward said feed rollers, no power will be transmitted from said wheels to said delivery rollers, and with the movement of said frame away from said rollers, said delivery rollers will be actuated.

20. A web feeding and collecting mechanism embodying therein supports for a plurality of rolls of printed strips or webs, a pair of feed rollers adapted to simultaneously draw a plurality of said strips or webs from the rolls thereof, a plurality of grippers each adapted to engage a strip or web, means whereby said grippers may be laterally adjusted to accommodate the machine to strips or webs of different widths, means whereby said grippers are reciprocated, operative connections between said last named means and said feed rollers, whereby said rollers will be actuated while said grippers are moving away from said rollers and will be inoperative while said grippers are moving towards said rollers, means arranged between said grippers and the delivery point of the machine, whereby said strips or webs, with the printed matter 90 thereon in register, are brought together and collectively fed in unison, fixed holding grippers between said first named grippers and said last named means, and actuating means for said last named means whereby it will be operative when said grippers are operative to feed the strips or webs, and will be inoperative when said grippers are inoperative.

21. A web feeding and collecting mechanism embodying therein supports for a plurality of rolls of printed strips or webs, a pair of feed rollers adapted to simultaneously draw a plurality of said strips or webs from the rolls thereof, a plurality of grippers each adapted to engage a strip or web, means whereby said grippers are reciprocated, operative connections between said last named means and said feed rollers, whereby said rollers will be actuated while 100 said grippers are moving away from said rollers and will be inoperative while said grippers are moving towards said rollers, means arranged between said grippers and the delivery point of the machine, whereby 110 it will be operative when said grippers are operative to feed the strips or webs, and will be inoperative when said grippers are inoperative.

- said strips or webs, with the printed matter thereon in register, are brought together and collectively fed in unison, means adjacent said grippers and said last named 5 means adapted to apply adhesive adjacent an edge of said strips or webs respectively, and actuating means for said last named means whereby it will be operative when said grippers are operative to feed the strips 10 or webs, and will be inoperative when said grippers are inoperative.
20. A web feeding and collecting mechanism embodying therein supports for a plurality of rolls of printed strips or webs, a 15 pair of feed rollers adapted to simultaneously draw a plurality of said strips or webs from the rolls thereof, a plurality of grippers each adapted to engage a strip or web, means whereby said grippers are reciprocated, operative connections between 20 said last named means and said feed rollers, whereby said rollers will be actuated while said grippers are moving away from said rollers and will be inoperative while said 25 grippers are moving towards said rollers, means arranged between said grippers and the delivery point of the machine, whereby said strips or webs, with the printed matter thereon in register, are brought together and 30 collectively fed in unison, an adhesive reservoir, a plurality of wheels adjacent thereto and rotatable about a vertical axis, said wheels being positioned between said grippers and said last named means, means continuously applying adhesive to, and rotating, said wheels, and actuating means for 35 said last named means whereby it will be operative when said grippers are operative to feed the strips or webs, and will be inoperative when said grippers are inoperative.
21. A web feeding and collecting mechanism embodying therein supports for a plurality of rolls of printed strips or webs, a 45 pair of feed rollers adapted to simultaneously draw a plurality of said strips or webs from the rolls thereof, a plurality of grippers each adapted to engage a strip or web, means whereby said gripper are reciprocated, operative connections between 50 said last named means and said feed rollers, whereby said rollers will be actuated while said grippers are moving away from said rollers and will be inoperative while said 55 grippers are moving towards said rollers, means arranged between said grippers and the delivery point of the machine, whereby said strips or webs, with the printed matter thereon in register, are brought together and 60 collectively fed in unison, an adhesive reservoir, a plurality of wheels adjacent thereto and rotatable about a vertical axis, said wheels being positioned between said grippers and said last named means, means continuously applying adhesive to, and rotating, said wheels, and actuating means for 65 said last named means whereby it will be operative when said grippers are operative to feed the strips or webs, and will be inoperative when said grippers are inoperative.
22. A web feeding and collecting mechanism embodying therein supports for a plurality of rolls of printed strips or webs, a pair of feed rollers adapted to simultaneously draw a plurality of said strips or webs from the rolls thereof, a plurality of grippers each adapted to engage a strip or web, means whereby said grippers are reciprocated, operative connections between 70 said last named means and said feed rollers, whereby said rollers will be actuated while said grippers are moving away from said rollers and will be inoperative while said grippers are moving towards said rollers, means arranged between said grippers and the delivery point of the machine, whereby said strips or webs, with the printed matter thereon in register, are brought together and 75 collectively fed in unison, an adhesive reservoir, a plurality of wheels adjacent thereto and rotatable about a vertical axis, said wheels being positioned between said grippers and said last named means, a disk rotating in said reservoir and engaging said wheels respectively, means rotating said disk, and actuating means for said last named means whereby it will be operative when said grippers are operative to feed the strips or webs, and will be inoperative when said grippers are inoperative.
23. A web feeding and collecting mechanism embodying therein supports for a plurality of rolls of printed strips or webs, a pair of feed rollers adapted to simultaneously draw a plurality of said strips or webs from the rolls thereof, a plurality of grippers each adapted to engage a strip or web, each of said grippers comprising a platen having a slit therein, and a resilient tongue, said grippers being arranged one above another with said tongues in vertical alignment, whereby the tongue of one gripper will co-operate with the platen of the gripper immediately below, means whereby said grippers are reciprocated, said means being so set as to impart movement to said grippers slightly in excess of their normal feeding movement, operative connections between said last named means and said feed rollers, whereby said rollers will be actuated while said grippers are moving away from said rollers and will be inoperative while said grippers are moving towards said rollers, means arranged between said grippers and the delivery point of the 100

machine, whereby said strips or webs, with the printed matter thereon in register, are brought together and collectively fed in unison, and actuating means for said last 5 named means whereby it will be operative when said grippers are operative to feed the strips or webs, and will be inoperative when said grippers are inoperative.

In witness whereof I have hereunto affixed

my signature, in the presence of two sub- 10
scribing witnesses January, 1922.

RALPH C. JAPPE,
*Now by judicial change of name Ralph C.
Stevenson.*

Witnesses:

JOSEPH A. CIDMAN,
F. T. WENTWORTH.
